SLIPPER OR SIMILAR ARTICLE

John A. Lacek, Dolgeville, N. Y., assignor to Daniel Green Company, Dolgeville, N. Y.

Application October 24, 1950, Serial No. 12,699

Term of patent 7 years

(Cl. D7—7)

To all whom it may concern:

Be it known that I, John A. Lacek, a citizen of the United States of America, residing at the city of Dolgeville, county of Herkimer, and State of New York, have invented a new, original, and ornamental Design for a Slipper or Similar Article, of which the following is a specification, reference being had to the accompanying drawing, forming part thereof.

In the drawing:

Fig. 1 is a plan view of a slipper, showing my design; and

Fig. 2 is a side view, in elevation, thereof.

Both sides of the slipper have substantially the same appearance.

I claim:

The ornamental design for a slipper or similar article, substantially as shown and described.

JOHN A. LACEK.
